BUILDING

Robert P. Orr, Prairie Village, Kans., assignor to Butler
Manufacturing Company, Kansas City, Mo., a corpo-
ration of Missouri

Filed Nov. 14, 1961, Ser. No. 67,517

Term of patent 3½ years

(Cl. D13—1)

Fig. 2.

Fig. 6.

Fig. 5.

FIG. 1 is a front elevational view of a building showing my new design;

FIG. 2 is a side elevational view thereof;

FIG. 3 is an enlarged cross-sectional view thereof taken on line 3-3 of FIG. 1;

FIG. 4 is an enlarged fragmentary perspective view of the gable center piece;

FIG. 5 is an enlarged fragmentary perspective view of the left corner of the trim of FIG. 1;

FIG. 6 is an enlarged cross-sectional view taken on line 6-6 of FIG. 2.

The dominant features of my design reside in the building trim and brackets shown in full lines on the drawing. The side and rear of the building not shown

are substantially the same as the side and front shown in FIGS. 1 and 2.

I claim:

The ornamental design for a building, as shown and described.
